CLAIM

The ornamental design for a shoe tread, as shown and described.

DESCRIPTION

FIG. 1 is a bottom view of a left shoe illustrating the shoe tread design of the present invention;

FIG. 2 is bottom view of a right shoe thereof;

FIG. 3 is a right side view thereof;

FIG. 4 is a left side view thereof;

FIG. 5 is a rear view thereof;

FIG. 6 is a front view thereof;

FIG. 7 is a side view thereof; and,

FIG. 8 is a cross sectional view of a portion of the shoe taken along the lines 8-8 in FIG. 1.

FIG. 8 illustrates the environmental structure of the portion of the shoe taken along the lines 8-8 in FIG. 1 with the understanding that the interior structure shown in FIG. 8 forms no part of the claimed design.
